HAIR TEASING COMB

Linda K. Davis, Rte. 4, Box 184, Abingdon, Va. 24210

Filed Jan. 27, 1975, Ser. No. 544,659

Term of patent 14 years

Int. Cl. D28—03

U.S. Cl. D86—8

Fig. 1

Fig. 2

Fig. 3

Fig. 4

FIG. 1 is a side elevational view of a hair teasing comb showing my new design;

FIG. 2 is a top plan view thereof;

FIG. 3 is an end elevational view thereof as seen from the left side of FIG. 1; and

FIG. 4 is an end elevational view thereof as seen from the right side of FIG. 1.

The side of the hair teasing comb opposite to that illustrated in FIG. 1 comprises a mirror image of FIG. 1.

I claim:

The ornamental design for a hair teasing comb, substantially as shown and described.
